UNITED STATES PATENT OFFICE.

RALPH A. SCHOENBERG, OF NEW YORK, N. Y.

MEANS FOR OPERATING SWITCH MECHANISMS.

1,229,530.

Specification of Letters Patent. Patented June 12, 1917.

Application filed August 13, 1915. Serial No. 45,406.

To all whom it may concern:

Be it known that I, RALPH A. SCHOENBERG, of New York, in the county and State of New York, have invented new and useful 5 Means for Operating Switch Mechanisms, of which the following is a specification.

My invention relates to means for operating switch mechanisms and one feature thereof consists in using a buckling spring 10 as a part of the switch mechanism.

Another feature consists in a rocking or oscillating circuit controlling member operated by a longitudinally movable support which in the forms shown is a threaded 15 shell to receive a lamp or attachment plug.

In the accompanying drawings:

Figure 1 is a central longitudinal sectional view of a socket for incandescent lamps embodying one form of my invention.

20 Fig. 2 is a side elevation of the body and screw shell of the socket shown in Fig. 1.

Fig. 3 is a sectional detail.

Fig. 4 is a plan view of the body of the socket shown in Fig. 1.

25 Fig. 5 is a central longitudinal sectional view of a lamp socket embodying another form of my invention.

Fig. 6 is a side elevation of the body and screw shell of the socket shown in 30 Fig. 5.

Fig. 7 is a section on line 7-7 of Fig. 6.

Fig. 8 is a section on line 8-8 of Fig. 5.

Fig. 9 is a central longitudinal sectional view of a lamp socket embodying another 35 form of my invention.

Fig. 10 is a side elevation of the body of the lamp socket shown in Fig. 9.

Fig. 11 is a plan view of the body of the lamp socket shown in Fig. 9.

40 Fig. 12 is a perspective view of the rocker of the lamp socket shown in Fig. 9.

Figs. 13 and 14 are details showing modifications.

In Figs. 1, 2, 3 and 4 of the accompanying drawings I have shown my invention as embodied in a lamp socket and in said figures A represents the exterior sheet metal shell which for convenience in assembling and disassembling the socket, is made in two 50 parts, as usual. The shell A has a lining B of insulating material surrounding a body C and screw shell D. For convenience the body C is made in two parts fastened together by three bolts c, c' and c''. In accordance with the present invention the body

C is immovably held in position within the lining B by reason of its close fit with said lining and by means of two annular shoulders c³ and c⁴ provided upon the inside of the lining, while the screw shell D is slidably mounted within the lining so as to be movable longitudinally toward and from the body C.

The screw shell D has a sheet metal contact E secured to its inner end, said contact occupying a longitudinal groove c⁵ provided upon the outer side of body C and being made near one end with a longitudinal slot c⁶ to receive a stud c⁷ projecting outwardly from a contact F.

The contact F also occupies the groove c⁵ and is always in engagement with the contact E, said contact F being made with a lateral extension near its lower end that is clamped immovably to the body C by means of the bolt c'. At its upper end the contact F is also made with an arm extending laterally into a chamber c⁸ provided within the body C. Within this chamber and alongside of the arm f is another arm g which is the laterally bent end of a contact G occupying a recess c⁹ formed upon the outside of body C and clamped within said recess by the bolt c.

The two arms f and g constitute two terminals which coöperate with a movable bridge piece H herein shown as a yoke pivotally supported by a pintle I on which the yoke is loosely mounted. The pintle I is supported near its ends by a pair of arms i integral with a sleeve i' pocketed within a chamber c¹⁰ that is provided within body C and which communicates with the chamber c⁸. The bolts c' and c² may serve to clamp the two parts of the body C firmly against the sleeve i' so that the latter is held against displacement within the body.

Within the lower end of the sleeve i' is mounted a plunger i² of insulating material such as hard rubber, and between this plunger and an inturned flange at the upper end of the sleeve is arranged a light spring i³ which normally holds the plunger i² at the lower end of the sleeve with the ends of a pin i⁴ carried by the plunger in engagement with the lower ends of two slots i⁵ formed in sleeve i'.

The screw shell D is made with the usual center contact d and this contact is always in engagement with a spring contact K fas-

tened to the body C by means of the bolt c^2 , with its free end arranged between the lower end of the plunger i^2 and center contact d .

The bolts c and c^2 serve as binding posts 5 to which the lead wires L and M are secured.

Rigidly secured to the pintle I between the two arms of bridge yoke H is a rocker N formed with a switch point n and two 10 shoulders n' and n^2 , one at each side of the base of the switch point. The switch point n and the two shoulders n' and n^2 coöperate with a spring blade O whose lower end is rigidly secured to the inner end of the plunger i^2 . So far as the function of this blade 15 O is concerned said blade is rigid so far as endwise pressure upon it is concerned, but it is laterally flexible at its upper end, the lower end of said blade being held rigidly 20 against lateral play by the plunger. The pintle I also has rigidly secured to it the upper end of a flat buckling spring P whose lower end is seated at the bottom of a V-shaped pocket c^{10} communicating with the 25 chamber c^8 , said spring being slightly greater in length than the distance between pintle I and the bottom of the pocket so that it normally occupies a bowed position yieldingly holding one arm of the rocker N 30 against one or the other of a pair of stop shoulders c^{11} and c^{12} provided on the body C. The rocker N carries a laterally projecting pin n' which operates a slot h formed in one arm of the bridge yoke H so that said 35 yoke and rocker are connected by said pin and slot but with provision for limited relative swinging movement.

In the drawings the bridge yoke H is shown out of engagement with the arms f 40 and g . When, however, it is desired to electrically connect the two arms f and g inward manual pressure is exerted upon the lamp (not shown) held by screw shell D and the inward movement of said shell acts 45 through center contact d and spring K to shove plunger i^2 and spring blade O toward rocker N against the pressure of the spring i^3 . The free end of spring blade O strikes the switch point P and the latter deflects the 50 end of the blade sidewise against the shoulder n' after which continued endwise movement of the blade swings rocker N and pintle I in a clock-wise direction against the yielding resistance of the buckling spring P. 55 As the rocker N is thus shifted the pin n' travels along the slot h and as soon as spring O has been buckled to the point where its middle portion is about to snap or snap 60 toward the opposite side of the body, the pin n' comes into engagement with the upper end of slot h so that when said spring does snap across toward the opposite side of the body it swings the rocker N beyond the position to which it was moved by the blade O 65 and against stop shoulder c^{12} . During this

movement of the rocker under the influence of the buckling spring P the pin n' lifts bridge yoke H into engagement with arms f and g . This closes the circuit through the lamp held by screw shell D, said circuit being traced as follows:—from lead wire L through contact G, arm g , bridge yoke H, contact F, contact E and screw shell D to and through the lamp and from the latter through center contact d , spring contact K 70 and bolt c^2 to the other lead wire M. As soon as pressure is removed from the lamp the spring contact K shoves the screw shell D and lamp back to their outermost positions again while the spring i^3 returns plunger i^2 to its normal position at the lower end of its sleeve. As will be clear the switch point n is shifted to the opposite side of the path of the free end of the spring blade O 75 when rocker N is thus operated. 80

When it is desired to open the circuit of the lamp at $f-g$ said lamp is again pushed inwardly and this time the switch point n guides the free end of the blade O laterally into engagement with the shoulder n^2 so 90 that said blade swings the rocker N in the opposite direction buckling the spring P in the opposite direction with the rocker moving free of bridge yoke H until the spring P is about to snap toward the opposite side 95 of the body. When said spring makes this snap movement the pin n' acting through the end of slot h swings the bridge yoke H out of engagement with arms f and g . 85

The pin and slot connection c^6-c^7 serves 100 to limit the movement of the screw shell toward and from body C.

In Figs. 9, 10, 11 and 12 I have shown another form of my invention comprising a rocker N' which directly controls the contact arms f and g , and which is itself operated and controlled by a single coiled spring O'. The rocker N' is made from a single piece of sheet metal and comprises two semi-circular side pieces n^3 united by a cross-bar 110 n^4 at each end of which is a depending wing n^5 , said wings and cross-bar forming a pocket to receive a ball o attached to one end of the spring O'. The opposite end of the spring O' is seated in a pocket i^7 115 formed in the upper end of a plunger i^6 slidably mounted in the body C'. At its lower end the plunger i^6 rests against a spring contact K' that is connected with one of the lead wires and adapted to directly 120 engage the center contact or terminal of the lamp. The spring O' holds the flat side of the rocker N' against one or the other of a pair of adjoining relatively oblique walls c^{13} and c^{14} bordering the pocket within 125 which the rocker is arranged, said rocker, when operated as presently to be described, swinging or rocking on the apex, c^{15} at the junction of said walls toward and from the contact arms f and g . Normally the springs 130

O' and K' hold the screw shell D' at the limit of its outward movement.

The pocket within which the ball o is arranged is wider than the diameter of said ball so that when the rocker is resting against one or the other of the walls c¹³ or c¹⁴ the spring O' occupies an oblique position with its ball o at one end of said pocket. In the drawings the rocker N' is shown out of engagement with the contact arms f and g but when it is desired to close the circuit through the lamp the latter is pushed inwardly and acts through contact K' and plunger i⁸ to shove the lower end of the spring O' inwardly on a line that is off-set relatively to the ball o with the result that spring O' is bowed toward the left. This bowing of the spring is due to the peculiar manner in which it is thus compressed causing its upper end to exert a sidewise pressure on the rocker which tilts the latter on the apex c¹⁵ toward the arms f and g. As soon as the bar n⁴ begins to incline in a direction opposite to that shown the ball o slides quickly to the opposite end of the pocket within which it is located, passing from one side of the apex c¹⁵ to the opposite side and giving a quick or snappy movement to the latter part of the travel of the rocker. When it is desired to open the circuit of the lamp the latter is again pressed inwardly and the spring O' acts as before only in the opposite direction.

In the form of my invention shown in Figs. 5 to 8, inclusive, the body of the socket comprises two blocks of porcelain 1 and 2 fastened together by means of two bolts 3 and 4. The meeting faces of the two blocks 1 and 2 are formed with longitudinal registering grooves 5 within which is an endwise movable stem 6 having its lower end fastened to but insulated from a screw shell 7 adapted to receive within it the threaded base of an incandescent lamp or of a coupling member. The lower end of the stem 6 extending through the end wall 8 of shell 7 and its extremity 9, which is centrally disposed, serves as a terminal to engage the center contact of the lamp or coupling member.

The stem 6 is made with a reduced portion 10 extending through a perforation 11 provided near the middle of a spring bow 12 and at one end of this reduced portion 10 is an annular shoulder 13 while at the opposite end thereof is an annular shoulder 14. The spring bow 12 is pocketed within registered recesses 14 provided in the two blocks 1 and 2 and the ends of said spring bow are free to rock or pivot in the V-shaped sockets 15 at the ends of the recesses 14.

The spring bow 12 is formed with a laterally projecting arm 16 which constitutes the movable contact of the switch, and this contact 16 cooperates with a stationary contact

17 fastened to the outside of block 1 by the bolt 3. With the spring bow 12 occupying a position shown in Fig. 1 the contact 16 is out of engagement with the stationary contact 17 and when said bow is sprung upwardly beyond a "dead center line" extending through the two sockets 15, the movable contact 16 slides up onto the stationary contact 17 and closes the circuit. When the spring bow 12 is sprung downward past the dead center the movable contact 16 is carried out of engagement with the stationary contact 17 and the circuit is opened. The spring bow 12 may be sprung back and forth across the dead center line by moving the device connected with screw shell 7 toward and from the body made up of the two blocks 1 and 2, the shoulder 14 shoving the middle of the spring bow 12 past the dead center when screw shell 7 is moved toward the body and the shoulder 13 shoving the middle portion of the spring bow 12 past the dead center when the screw shell 7 is moved in the opposite direction. The two shoulders 13 and 14 are separated so that when screw shell 7 is pulled outward to open the circuit the shoulder 13 will push the middle portion of the spring bow 12 just past the dead center line whereupon the spring bow will snap forward along the reduced portion 10 of stem 6 thereby producing a quick break between the contacts 16 and 17.

To the inner end of the screw shell 7 is fastened a contact 18 bearing at its inner end upon a contact 19 fastened by means of the bolt 4 to the outside block 2. The contact 19 carries a pin 20 occupying a slot 21 provided through one end of the contact 18. This pin and slot connection between the contacts 18 and 19 interlocks the screw shell 7 and the body of the device with provision for limited relative movement.

One of the lead wires 22 is fastened to the bolt 3 while the other lead wire 23 is fastened to the bolt 4. Thus it will be seen that when contacts 16 and 17 are closed the circuit extends from lead wire 22 through contact 17, contact 16, spring bow 12, stem 6, through the device connected with screw shell 7 back to the latter and thence through contacts 18 and 19 to the other lead wire 23.

The working parts of my improved coupling member or socket may be inclosed by a housing consisting of a two-part sheet metal shell 23 having a lining 25 of insulating material.

In Fig. 13 I have shown a modification having a flat direct acting buckling spring O² seated at its lower end in a pocket i⁸ provided at the inner end of the plunger i⁸ and seated at its upper end in a V-shaped pocket n⁶ provided on a bridging rocker N². This construction has the same mode of operation as that shown in Fig. 5, except that the

upper end of the spring O^2 does not slide sidewise within the pocket n^6 .

In Fig. 14 I have shown a modification which is the same as shown in Fig. 5 except that the lower end of the buckling rocker operating spring O^3 has attached to it a ball o' seated in a pocket i^9 formed upon the inner end of the plunger i^{10} said pocket being wider than the diameter of the ball. When the plunger i^{10} is forced inwardly the buckling of the spring O^3 operates the rocker as before but when the upper end of the spring O^3 slides laterally in one direction the ball o' at the lower end thereof will slide laterally in the opposite direction. This provides for greater normal obliquity of the spring O^3 than is the case with the spring O' thereby giving greater and more definite buckling effects.

20 What I claim is:

1. A device of the character described comprising a pivotally supported rocker made with a switch point and with two shoulders, one at each side of said point; a spring connected with said rocker; an endwise movable laterally flexible blade coöperating with the switch point and shoulders of said rocker, a reciprocating carrier for said blade; a pair of contacts and a movable supported bridge member connected with and operated by said rocker.

2. A device of the character described comprising a pivotally supported rocker made with a switch point and with two shoulders, one at each side of said switch point; a buckling spring connected with said rocker; an endwise movable laterally flexible blade coöperating with the switch point and shoulders of said rocker; a body; a pair of contacts mounted on said body; a movably supported bridge member con-

nected with and operated by said rocker, and a lamp holding screw shell connected with one of said contacts, the other contact being adapted to be connected with one of the lead wires. 45

3. A device of the character described comprising a pivotally supported rocker made with a switch point and with two shoulders, one at each side of said switch point; a buckling spring connected with said rocker; an endwise movable laterally flexible blade coöperating with the switch point and shoulders of said rocker; a body; a pair of contacts mounted on said body; a movably supported bridge member operated by said rocker; a lamp holding screw shell connected with one of said contacts, the other contact being connected with one of the lead wires; a center contact mounted on 55 but insulated from said shell, and a spring contact engaging said center contact and connected with the other lead wire. 60

4. A device of the character described comprising a pivotally supported rocker made with a switch point and two shoulders, one at each side of said point; a buckling spring connected with said rocker; an endwise laterally movable flexible blade coöperating with the switch point and shoulders 70 of said rocker; a pair of contacts; a movably supported bridge member connected with said rocker with provision for limited relative movement, and a lamp holder longitudinally movable to operate said blade, alternate inward movements of said holder acting through said blade to shift the rocker in one direction and the other inward movements of said holder acting through said blade to shift said rocker in the opposite 75 direction. 80

RALPH A. SCHOENBERG.
